His Attorneys.

Patented Dec. 6, 1927.

1,651,370

UNITED STATES PATENT OFFICE.

JOHN K. BRODERICK, OF KIRKWOOD, MISSOURI.

REVERSIBLE CUFF.

Application filed May 20, 1926. Serial No. 110,317.

This invention relates to reversible cuffs.

An object of the invention is to provide a reversible cuff attached to the sleeve in such a manner that one side edge of the cuff is 5 extended beyond the sleeve as the exposed edge, while the other side edge of the cuff overlies the sleeve, so that the cuff may be turned to position in which the second side edge of the cuff is exposed and the first 10 side edge of the cuff extends into and is covered by the sleeve.

Another object of the invention is to provide a reversible cuff of the desired width comprising a number of plies of material, 15 and means for hinging the cuff with the sleeve approximately midway of the width of the cuff; whereby when one side edge of the cuff is extended for use the other side edge surrounds the sleeve, and when the 20 other side edge is extended for use the first side edge extends into the sleeve.

Another object of the invention is to provide a reversible cuff of novel construction and secured to the sleeve in a novel relationship, permitting either side edge of the cuff to be extended for use so that in one position of the cuff one of the side edges thereof extends around the sleeve, and when the 25 second side edge of the cuff is extended for use the other side edge of the cuff extends into the sleeve.

Other objects of the invention will appear from the following description, reference being made to the accompanying drawing in 30 which—

Fig. 1 is a view showing a portion of a shirt sleeve having my improved cuff applied thereto.

Fig. 2 is a view, partly in section, showing 40 the construction of the cuff and its attachment to the sleeve.

Fig. 3 is a sectional view, the parts being enlarged and extended to show their relationship to each other.

The sleeve 1 is of conventional construction and has my new and improved cuff attached thereto in a novel relationship to achieve the objects stated. As shown, the cuff comprises a ply of material 2, and an 45 other ply of material 3, and a third ply of material 4. The end portion 5 of the sleeve extends between the adjacent edges of the plies 3 and 4 and between the plies 2 and 3.

The outer edges 6 of the plies 2 and 3 are 50 folded between the plies, one of said folded edges embracing the edge of the part 5 of

the sleeve. The plies and the folded portions thereof and the extended portion 5 of the sleeve are secured together by a line of stitching 7. A ply of material 8 may be 60 interposed between the plies 2 and 4 and extended beyond the inner edge of the ply 3 and between the ply 2 and the sleeve portion 5. The three parts 5 and 8 may be secured together by a line of stitching 9, 65 after which the line of stitching 10 is formed to attach together the interfolded edge 11 of the ply 3 and the plies 2, 3, 5 and 8.

The part 12 of the sleeve connecting the same with the part 5 is between the adjacent 70 edges of the plies 3 and 4 and forms a pivotal connection permitting the cuff to be turned to extend either wearing edge of the cuff for use. The edge 13 of the ply 4 adjacent to the sleeve pivot 12 is folded between the 75 plies 4 and 8, and a line of stitching 14 passing through the plies 2, 4 and 8 and the folded edge 13 forms a permanent attachment.

The inwardly folded edges 15 at the outer 80 edges of the plies 2 and 4 are secured together and to the ply 8 by a line of stitching 16 which may be a continuation of the line of stitching indicated as passing along the ends of the cuff at 17.

The number of plies may be varied to meet the requirements of a soft or a stiff cuff, as desired, and still leave the cuff reversible to expose the ply 2 as the outer ply of one 90 wearing edge of the cuff and the ply 4 as the outside of the other wearing edge of the cuff. Reversal of the cuff is obtained by turning the cuff upon the pivot portion 12 of the sleeve to place the wearing edge of the cuff, comprising the plies 2 and 3, 95 within the cuff and extending the other wearing edge of the cuff, comprising the plies 2 and 4, to position for use, thus exposing the ply 4.

The specific construction and method of 100 turning and attaching the plies at 12 together with their length and extent may be varied within equivalent limits and the number of plies may be optional to provide a cuff of different styles without departure 105 from the nature and principle of the invention.

What I claim and desire to secure by Letters Patent is:—

1. The combination with a garment sleeve, 110 of a reversible cuff having two wearing edges and comprising for one edge an inner ply

and an outer ply of material confining the end of the sleeve between them and stitched together and to the sleeve at their outer edges and at the inner edge of said inner 5 ply; a third ply of material terminating short of the inner edge of said inner ply and stitched to said outer ply near the line on which the inner edge of said inner ply is 10 stitched to the sleeve as aforesaid; and a line of stitches securing the outer edges of said third ply to the outer edges of said outer 15 ply.

2. A reversible cuff having two wearing edges and comprising a wide ply of material forming the outer side of the cuff portion at one wearing edge of the cuff, a second 15 ply of material having its marginal edges secured to said wide ply and forming the inner side of cuff portion of which said wide 20 ply is the outer side, a third ply of material attached to said first ply having its inner edge terminating short of the inner edge of said second ply, and arranged to

form the exposed surface of the opposite wearing edge when the opposite edge is used as a wearing edge, a fourth ply of material secured between said first and third plies and extending between said first and said second plies, and means connecting said cuff to a sleeve and to said fourth ply. 25

3: A reversible cuff having two wearing edges each composed of a plurality of plies of material and one of which plies extends the full width of the cuff from one wearing edge to the other and two of which plies are 30 relatively narrow and extend from the respective wearing edges and have their inner edges terminating short of each other in spaced relationship and secured to said full width ply by a row of stitches for each of 40 said narrow plies, in combination with a sleeve having a portion thereof extending between the adjacent edges of said narrow plies and secured to and forming a pivotal connection for the cuff. 35

JOHN K. BRODERICK.
